PRINTING TELEGRAPH APPARATUS

Max Dressler, Berlin-Haselhorst, and Willy Skawran, Berlin-Spandau, Germany, assignors to Siemens & Halske, Aktiengesellschaft, Siemensstadt, near Berlin, Germany, a corporation of Germany

Application September 1, 1937, Serial No. 161,958
In Germany September 1, 1936

8 Claims. (Cl. 178—53.1)

This invention relates to printing telegraph apparatus and more particularly to telegraph apparatus wherein the individual character symbols are composed of impulses corresponding to portions of the symbols.

An object of the invention is the provision of a transmitter which is simple, compact, and reliable for the precise transmission of groups of impulses identified with and peculiar to each character symbol.

A feature of the invention resides in the arrangement of the transmitting and receiving components in a unitary unit.

The above and other objects of the invention are accomplished through the provision of an impulse transmitter including a plurality of discs or cams, one individual to each character to be transmitted, and each having its periphery formed distinctly for each character, which are effective, depending on a key lever of a keyboard depressed, on a single contact to cause thereby the precise transmission of impulses symbolic of the character for each key lever. When used in start-stop systems, the stop impulse is generated by a cam operated contact when the cam shaft on which the character cams are also mounted is in its rest or normal position. When the cam leaves its rest position, the contact is opened and the start impulse is transmitted. A special contact may also be provided whereby the release circuit is opened in response to a start impulse when the unit includes both transmitter and receiver. Disturbance by operation of the remote transmitter as the result of the operation of the transmitting contact is thus avoided.

A full and complete understanding of the invention may be had from the following description, taken in conjunction with the accompanying drawings, wherein

Fig. 1 shows diagrammatically the arrangement of the receiving and transmitting components of printing telegraph apparatus in accordance with the present invention;

Fig. 2 shows diagrammatically a certain portion of the transmitter; and

Fig. 3 shows a further portion or embodiment of the transmitter.

As symbolized in the drawings, referring particularly to Fig. 1, the transmitter includes a plurality of key levers 5 arranged in several rows as is customary in transmitters for telegraphic communication. Each of the key levers 5 is pivoted on a rod such as 6, it being, of course, understood that there is a rod 6 individual to each horizontal row of key levers 5. Attached to

each key lever 5 is a vertically extending bar 7 which is normally under the tension of a spring 8 and which has near its free end a notch 9.

As indicated, there is a bar 7 individual to each key lever 5 of the keyboard. Consequently, according to an embodiment of the invention a cam 10 mounted on a shaft 11 is provided individual to each of the bars 7. The periphery of each of the cams 10 is cut differently. In fact, the periphery of each cam 10 is cut distinctively 10 for each character, impulses corresponding to which are to be transmitted and recorded by the receiver connected to the signalling channel which may be either a wire channel or a radio channel. In other words, there is a cam 10 individual to each of the characters, impulses corresponding to which are to be transmitted to a distant station.

Transmission of impulses allocated to each of the characters is achieved through the operation 20 of a single set of contacts 12 which, as shown in Fig. 1, are included in conductors 13 and 14 containing a source of current 15. Consequently, when the contacts 12 are opened and closed, impulses corresponding thereto will be impressed 25 from the source of current 15 on the conductors 13 and 14. Operatively connected to contacts 12 is a counterpoise 16 pivoted at 17 and having a flange at its free end which is disposed opposite the notch 9 formed in each of the bars 7. Counterpoise 16 extends transversely of the key lever 5 and is common to all of the bars 7; that is, each of the bars 7 controls the operation of counterpoise 16 and consequently the actuation of contacts 12.

Referring again to Fig. 1, it is noted that closed contacts 18 are connected in parallel with respect to contacts 12. Contacts 18 are operated by a universal bar 19 common to and positioned below the key levers 5. With such a construction, 40 when any one of the key levers 5 is depressed, universal bar 19 is also operated and contacts 18 are opened, thus removing their effectiveness from contacts 12 to render contacts 12 effective.

Also mounted on shaft 11 is a cam 20 which, in its normal position, cooperates with a pull bar 21 to hold contacts 12 normally closed when the shaft 11 is in its rest position, as is common practice in start-stop telegraph systems. With contacts 12 closed under such conditions current is normally applied to conductors 13 and 14, which is symbolic of the rest condition of the system. Bar 21 is urged in cooperation with cam 20 by a spring 22 and has formed in its upper free end 50 a notch 23. Formed in the end of bar 21 oppo-

site to the end wherein the notch 23 is formed is a projection 24 which is normally engaged by a bail 25 carried by a pivoted lever 26 which normally is under the action of a spring 27. Bail 25, being common to each of the key levers 5, will be depressed upon the depression of any of the key levers and will thus operate against the action of spring 27 and cause movement of bar 21 sufficient to bring notch 23 in alignment with the projection formed on the free end of counterpoise 16. Under such conditions, the counterpoise 16 will be shifted from the position shown in Fig. 2 to the position shown in Fig. 1, wherein the contacts 12 are opened and current is removed from the line. Inasmuch as contact 18 is also opened upon the depression of a key lever 5 and the operation of bail 19, the circuit including the conductors 13 and 14 is opened and the telegraph apparatus is started into operation.

The transmitting cam shaft 11 must be arrested after each revolution so that a symbol or a group of impulses indicative thereof is not repeatedly transmitted if the key therefor is held depressed for a period longer than the time required for the transmitting shaft 11 to complete one cycle of rotation. In order to achieve such a result, a lever 28 which cooperates with cam 20 and which has secured to its lower end a pin 29 in engagement with the lower extremity of bar 21 is provided. Lever 28 is normally under the tension of a spring 30 which tends to hold pin 29 out of engagement with the lower end of bar 21. However, upon the rotation of cam 20, lever 28 is rotated about its pivot against the action of spring 30 for moving bar 21 sufficiently to effect the disengagement of projection 24 from bail 25. Bar 21 thereupon is restored to its vertical normal position by the action of its spring 22. Subsequently, contacts 12 are closed by cam 20 and current is again applied to conductors 13 and 14 for the energization of the start magnet through which the transmitting shaft 11 is arrested.

Also secured to transmitting shaft 11 is a cam 32 which operates a lever 33 against the action of a spring 34. The lower end of lever 33 carries a bail 35 which extends transversely of each row of key levers and which serves to maintain the depressed key lever operated and to prevent the operation of another key lever pending the restoration of the previously depressed key lever 5 to its normal or undepressed condition. Such a result is achieved by forming in the upper edge of each of the key levers 5 a hook portion 36 which is designed to cooperate with bail 35 in a manner such that the depressed key lever will be maintained depressed for the cycle of rotation of transmitting shaft 11 and the other undepressed key levers will be locked against depression for the cycle of operation of the transmitting shaft 11.

Referring now to Fig. 1, the line conductors 13 and 14 extend, depending upon whether contact blade 38 is in contact with switch member 39 or 40, through the winding of electromagnets 41 or 42, respectively. Electromagnet 41 which constitutes the start magnet, is normally energized due to the fact that the contacts 12, as shown in Fig. 2, are normally closed. Consequently, stop member 43 secured to the armature of electromagnet 41, normally lies in the path of stop lug 44 secured to transmitting shaft 11. Under such conditions, when a key lever is depressed, bar 21 will be operated. As previously described, counterpoise 16 will rotate about its pivot 17 and

contacts 12 will be opened. Current is thereupon removed from the line conductors 13 and 14 and electromagnet 41 will be deenergized. Upon de-energization, the armature of electromagnet 41 moves stop projection 43 out of the path of stop lug 44 and releases transmitting shaft 11, which normally tends to rotate by power communicated from a motor through a friction clutch which is released for rotation.

Electromagnet 42 constitutes the receiving or printing magnet of the receiver and responds to the operation of contacts 12 in accordance with the rotation of cam 10 rendered effective on bar 7 through the operation of a particular key lever 5. Electromagnet 42 controls a pressure blade or hammer 45 which cooperates with a rotating spiral 46 to record the character symbols, as is fully disclosed in Patent No. 2,046,328 to E. E. Kirschmidt et al., granted July 7, 1936. Spiral drum 46 is secured to shaft 47 which also carries a gear 48 meshed with a gear 49 secured to shaft 50 of the receiving component of the combined transmitter and receiver. Shaft 50, of course, is released upon the de-energization of electromagnet 41, since power for rotating shafts 11 and 50 is communicated from a common source of power through a friction clutch common to the shafts 11 and 50.

Also secured to shaft 50 is a cam 51 which cooperates with switch members 39 and 40 to cause their engagement with switch blade 38; that is, when the cam 51 is in its normal or rest position, switch blade 38 contacts switch member 39 to include the winding of electromagnet 41 in the conductors 13 and 14. However, during rotation of cam 51, switch member 40 is moved into contact with switch blade 38, so that the winding of electromagnet 42 is included in the conductors 13 and 14 and the winding of electromagnet 41 is excluded therefrom.

Under certain conditions it may be found desirable to utilize positive and negative current conditions which are used in wireless transmission. To make possible the use of apparatus constituting a part of the present invention for such purpose, an additional contact 52, shown in dotted outline in Figs. 1 and 2, may be provided. With the arrangement of the contacts as indicated, transmission may be accomplished through the use of polar signals.

While the invention has been described in conjunction with a specific type of apparatus, it is obvious that it is not restricted to such specific apparatus for it may be embodied in a variety of different forms of apparatus without departing from the spirit and scope of the invention.

What is claimed is:

1. A telegraph transmitter including a plurality of key levers, a plurality of members one for each character, impulses indicative of which are to be transmitted, means operated by said key levers for rendering said members individually effective, and means common to all of said members and operated by each member through said means for transmitting impulses in accordance with the operated member and distinctive of the character identified therewith.

2. A telegraph transmitter including a plurality of key levers, an operating shaft, a plurality of cams on said shaft each having its periphery formed with projections corresponding to the individual impulses characteristic of the character allocated thereto, means operated by said key levers for rendering said cams individually effective, and means common to all of said cams and operated by each cam through said means

for transmitting the impulses determined by the projections on the periphery of the then effective cam.

3. A telegraph transmitter including a plurality of key levers, an operating shaft, a plurality of cams secured to said shaft each of said cams having its periphery formed with projections corresponding to the individual impulses representative of the character to which said cam is allocated, means operated by the key levers for rendering said cams individually effective, a start cam also secured to said shaft and arranged to be effective prior to said plurality of cams, and means operated by the cams identified with the respective characters and the start cam for transmitting impulses in accordance with the effectiveness of said cams.

4. A telegraph transmitter including a plurality of key levers, an operating shaft, a plurality of cams secured to said shaft each of said cams having its periphery formed with projections corresponding to the individual impulses indicative of different characters, a universal bail, a start cam also secured to said shaft, a transmitting contact, and means operated by said bail through the operation of a key lever for rendering said start cam effective to effect through the operation of said contact the transmission of a start signal and thereafter one of said plurality of cams for the transmission of the character identifying impulses.

5. A telegraph transmitter including a plurality of key levers, an operating shaft, a plurality of character cams secured to said shaft each of said cams having its periphery formed with projections corresponding to the impulses individual to each character, a start cam also secured to said shaft, a transmitting contact, means common to the cams identified with the character and the start impulses, and means operated by said key levers for rendering said start cam and said character cams effective through said common means on said contact successively to effect the transmission of a start impulse followed by a series of character impulses.

6. A telegraph transmitter including a plurality of key levers, an operating shaft, a plurality of members carried by said shaft each of said members being identified with a particular character and arranged to control the transmission of impulses identified with the character allocated thereto, means for causing the transmission of a start impulse, means controlled by each of said key levers for rendering the member individual thereto effective for the transmission of impulses for the character thereof, and means operated in timed relation with respect to said members for insuring that a stop impulse will be transmitted at the end of transmission of the character impulses regardless of the continued operation of the key lever through the operation of which the start impulse was transmitted.

7. A telegraph transmitter including a plurality of key levers, a plurality of members, one for each character, impulses indicative of which are to be transmitted, a single transmitting contact, means operated by said key levers for rendering said members individually effective on said contact, an additional set of contacts connected in circuit with said transmitting contact, and means operated upon the depression of any of said key levers for operating said additional contacts.

8. A telegraph system including a receiver comprising starting and printing mechanisms, and a transmitter including a plurality of members one for each character, impulses indicative of which are to be transmitted, a plurality of key levers, means operated by said key levers for rendering said members individually effective, means common to said members and operated by each member for transmitting impulses in accordance with the operated member, means operative upon the depression of a key lever for transmitting a start impulse, and means effective in response to a start impulse for rendering said starting mechanism ineffective and said printing mechanism effective.

MAX DRESSLER.
